UNITED STATES PATENT OFFICE.

JOHN W. MILLER, OF EL-DORADO, ARKANSAS.

PULLING DEVICE FOR GEARS AND THE LIKE.

Application filed April 24, 1926. Serial No. 104,475.

This invention relates to a pulling device adapted for use on gears, wheels and the like particularly in connection with automobiles or vehicles.

It is aimed to provide a novel construction wherein different jaws may be accommodated according to different automobiles or the work, wherein the jaws are efficiently held against accidental detachment although reversible, and wherein the construction is generally improved, simplified and rendered more efficient.

The more specific objects and advantages will become apparent from a consideration 15 of the description following taken in connection with accompanying drawings illustrating an operative embodiment.

In said drawings:—

Figure 1 is a view of the device in front 20 elevation;

Figure 2 is a view thereof in end elevation;

Figure 3 is a sectional view taken on the line 3—3 of Figure 1;

Figure 4 is a plan view of the device, with 25 the upper portion of the pulling screw shown in section.

Figure 5 is a vertical sectional view showing a different form of jaws in place;

Figure 6 is a detail sectional view taken 30 on the line 6—6 of Figure 1;

Figure 7 is a detail sectional view taken on the line 7—7 of Figure 1, and

Figure 8 is a detail sectional view taken 35 on the line 8—8 of Figure 5.

Referring specifically to the drawings, a suitable plate or stock is provided as at 10, being generally of H-shape in that it has a central hub 11 and pairs of spaced longitudinal arms 12 with longitudinal slots 13 therebetween. A pulling screw of any appropriate form is shown at 14 as screw threaded in the hub 11 and as having a head 15 for engagement by a wrench or tool to 40 impart rotation thereto. The free end of the screw may directly engage the work or it may engage a buffer block 16 as shown in Figure 5 and which is first applied against the work.

The upper surfaces of the arms 12 are 45 corrugated or provided with notches 14^a which are occupied by cross heads 15 of puller jaws 16. In order to prevent possibility of accidental turning of the jaws 16 in the slots 13, such jaws at the slots are preferably 55 square or otherwise polygonal in cross sec-

tion as best shown in Figure 6. Such jaws may be secured in any pair of the notches 14 according to the adjustment desired dependent on the size of the parts to be pulled 60 and such jaws may also be reversible from one side to the other side.

In order to hold the head 15 against danger of accidental detachment from the notches 14^a, a resilient holder plate 17 is 65 provided, which plate has depending hooks 18, resiliently clipping into notches 19, in the stock 10, thereby holding the plate 17 in place. Such plate 17 is made of resilient metal and has outwardly extending wings 70 20, which yieldingly bear on the cross head 15. Such construction enables the jaws to be readily lifted against the tension of the springs 20 in reversing the jaws or changing the position of the cross head 15 from one 75 pair of notches 14^a to another.

The said jaws may be arranged at any desired angle and have further means so as to prevent danger of displacement, particularly when the jaws are in engagement with 80 work. To this end, each jaw has a lug 21 extending laterally therefrom and in which a screw 22 is threaded. Such screws bear against blocks 23 bifurcated at 24 to embrace the jaws, as best shown in Figure 6. 85 By means of the screws 22, the blocks 23 may be screwed to the desired position for engagement with the stock.

The jaws 16 at their free ends are preferably deflected slightly inwardly as at 25 90 and they terminate in lugs 26. The reversal of the jaws would permit the lugs 26 to extend away from each other rather than toward each other as shown in Figure 1. Such formation of the jaws, is of course optional since the same will vary according to the work. For instance in the modified form of jaws shown in Figure 5, they are straight throughout and have lugs or heads 27 at their lower ends notched as at 28 and provided with projections 29 opposite thereto. This form of jaws, namely that of Figures 5 and 8, primarily adapt the tool for use on Ford automobiles.

It is obvious, that in use, the jaws at the 105 lugs 26 or 27 engage the work to be pulled and that the screw 14 is placed against a part to remain in place, and operated, so as to move the stock longitudinally of the screw and thereby remove the gear or other 110 part.

It will be obvious that no limitation is to

- be implied as to the work which may be accomplished. For instance, the device may pull the drive pinions, drive shaft sleeve, transmission clutch drum, main transmission 5 drive gear, the timing gear from a crank shaft or the like, and that where one pair of jaws will not accommodate the work, that the other pair may be substituted without material loss of time.
- 10 Various changes may be resorted to provided they fall within the spirit and scope of the invention.

I claim as my invention:—

- 15 1. A pulling tool of the class described having a head, a pulling screw carried by the head, jaws carried by the head capable of swinging movement thereon, lugs on said jaws, screws threaded in said lugs, and blocks carried by said screws and engaging the head to limit the swinging movement of said jaws.
- 20 2. A pulling tool of the class described having a head including spaced arms notched on their outer sides, jaws to engage the work 25 having cross heads engaging the notches, lugs on said jaws, screws threaded in said

lugs, and blocks carried by said screws and engaging the heads to hold the cross heads in the notches and limit the swinging movement of said jaws.

30 3. A pulling tool of the class described comprising a head, plates having hooks detachably engaging said head, resilient wings extending from the plates, and jaws to engage the work fastened against the head against accidental displacement by said wings.

35 4. A pulling tool of the class described having a head of H-shape, thereby providing a hub, and arms extending therefrom in parallel relation with slots therebetween, the outer surfaces of said arms having notches, said head having slots, a plate having hooks detachably engaging said slots, resilient wings extending from said hooks, a screw 40 threaded in the hub of said plate, and work-engaging jaws extending through said slots, said jaws having cross heads engaging said notches and in turn engaged by said wings.

45 In testimony whereof I affix my signature.

JOHN W. MILLER.
